UNITED STATES PATENT OFFICE

THOMAS C. STEPHENS, OF ST. LOUIS, MISSOURI

SMOKE-CONSUMING DEVICE

Application filed August 4, 1928. Serial No. 297,521.

The object of the invention is to provide a device to take air from the outside into the device, allow it to become heated while it is in the device, and then to distribute this heated air over the surface of the fire so it will mix with the gases coming from the fire, thereby allowing enough oxygen to mix with the gases so they may readily burn, and thus reducing the smoke going up the flue.

10 In the device, Fig. 1 is a perspective of half of the device proper; Fig. 2 is a top view of Fig. 1; Fig. 3 is a perspective of the other half of the device proper; Fig. 4 shows a top view of the cover for the part in Fig. 13; Fig. 5 is a side view of Fig. 4; Fig. 6 is a top view of the covering for the part in Fig. 1; Fig. 7 is a side view of Fig. 6; Fig. 8 is a top view of the parts shown in Figs. 1 and 3 when assembled; Fig. 9 is a cross sectional view of the complete device; Fig. 10 is a cross sectional view of the coupling used in the pipes leading to the fire; Fig. 11 is a cross sectional view of one of the pipes; Fig. 12 is a cross sectional view of the coupling assembled; Fig. 13 shows the device mounted in a furnace.

Fig. 1 shows a rectangular box 1, divided into three compartments by the walls 3. 2 are rectangular openings in the walls 3, and 30 also in the sides of the box. 12 are bolt holes thru which bolts pass to hold the device together. This box is made of cast iron.

Fig. 2 is a top view of Fig. 1. The bottom of the box 1 has five holes 4 drilled in it. 35 5 are bolt holes thru which bolts pass to hold the top on.

Fig. 3 shows a perspective of the other half of the device proper. It consists of two cast iron rectangular boxes, 6 6 joined together by the part 8. The hole, 4 in the center coincides with the center hole 4 in Fig. 2. 2 are rectangular openings of the same size as those in Fig. 1 and they coincide with the openings 2 in the walls of Fig. 1. 12 are bolt holes thru which bolts pass to hold the device together. They coincide with the holes 12 in Fig. 1.

Fig. 4 is a top view of the covering for the part shown in Fig. 3. It consists of a rectangular piece of metal 17, with the hole

9 drilled in the center of it. This hole is the one thru which the air enters into the device, and it coincides with the hole 9 in Fig. 6. The holes 10 are bolt holes thru which bolts pass to hold the top on.

55 Fig. 5 is a side view of the part described in Fig. 4. 17 is the rectangular metal top, 10 are the bolt holes, 9 is the intake hole.

Fig. 6 is a top view of the covering for the part described in Fig. 1. The metal top 18 has an offset 13 on it to fit over the part that is described in Figs. 4 and 5. The hole 9 is the intake hole and it must coincide with the hole 9 in Figs. 4 and 5 when the device is assembled. 10 are bolt holes thru which bolts 60 pass to hold the top on.

Fig. 7 is a side view of the top described in Fig. 6. 13 is the offset on the metal top 18. 9 is the intake hole and 10 are the bolt holes.

Fig. 8 is a top view showing the assembly 70 of the parts described in Figs. 1, 2, and 3. The part 1 fits into the space between the similar parts 6 6. The bolts 11 fit thru the holes 12. These bolt holes do not appear in this figure, but can be seen in Figs. 1 and 3. The holes 4 in the bottom are the holes thru which pipes pass that lead to the fire. Due to the fact that the hole 4 in the part 1 coincides with the hole 4 in the part 6, the center hole 4 in the figure is a continuous one that leads into the device. The holes 10 are bolt holes thru which bolts pass to hold the top on.

Fig. 9 is a cross sectional view of the device when it is assembled. 6 is the rectangular box described in Fig. 3 and 1 is the part described in Fig. 1. 17 is the top for 6 and is described fully in Figs. 4 and 5. 18 is the top for the part 1 and is described in Figs. 6 and 7.

13 are the bolts to hold the top on. 14 are the pipes leading from the device to the couplings and are described in Fig. 11. 21 are the couplings and are described in Fig. 10. 22 are the pipes leading from the couplings to the fire and are described in the assembly of the coupling in Fig. 12. 22 are the holes thru which air passes to the outside chambers of the device. 16 are the washers which fit over the pipes 14. 15 are the pins which fit thru a hole in the pipes. These pins hold the pipes 90 95 up. 19 is a pipe which fits firmly into 18 and 100

projects a little above the top of 18. 20 is a pipe that fits over 19 but does not fit over 19 so tight that it cannot be easily fitted on. 31 is the intake pipe that leads to the outside of the furnace. It is the same size as 19. The assembly and purpose of this pipe, 31, is explained in Fig. 13. If, when the sleeve 20 is fitted over the pipes 19 and 31, there is any space between the pipes and sleeve, it can be filled by packing asbestos in the space. It will be noted that the holes in the bottom of the device are larger than the pipes 14. This allows the pipes to bend a little at this point in case any one should come against it with anything.

Fig. 10 is a cross sectional view of the coupling which was designated as 21 in Fig. 9. It consists of two round cuplike parts 23 and 24 with the holes 26 and 27 in the top and bottom one respectively. On the side of each of 23 and 24 are projections thru which the bolts 25 pass to hold the coupling together. This outside connection of the pipes themselves preserves the full area of the pipes free from obstruction from the downward passage of the air to the fire.

Fig. 11 is a cross sectional view of the pipe that leads from the device to the coupling. 14 is the pipe with the pin 15 passing thru a hole in it. 16 is a washer which fits over the pipe 14 and is prevented from coming off by the pin 15. 28 is a washer on the other end of the pipe and is secured by spreading the end of the pipe 14.

Fig. 12 shows the assembly of the coupling with the pipes 14 and 22 in place. The pipe 14 fits thru a hole in the top of the part 23, but is kept from coming thru by the washer 28. It will be seen that there is a little space between the pipe 14 and the side of the hole. This is to allow the coupling to bend at this point to a small degree. 22 is a pipe leading from the coupling to the fire. It consists of a pipe 22 with a washer 30 fitted on the end of the pipe. The end of the pipe is then expanded to keep the washer 30 from coming off. It will be noticed that the pipe 22 is smaller than the hole in the coupling thru which it passes. This allows the coupling to bend at this point. This, combined with the play at the top of the coupling, makes the coupling flexible.

Fig. 13 shows the device installed in a furnace. 35 is the casing of the furnace, and 34 is the chamber that contains the fire. 31 is the intake pipe leading from the outside of the furnace to the device. 32 are L's in the pipe 31. The purpose of the pipe 31 is to supply air to the device inside the furnace from the outside. 33 shows the location of a damper in the pipe 31 to control the supply of air to the device. 29 are brackets placed on the inside of the chamber to support the device. 40 is the bottom or floor of the furnace. 37 represents the ash door and 36 represents the

fire door. 39 is the location of the grate of the furnace. 38 shows the location of the highest fire level. 6 is the part described in Fig. 3 and 1 is the part described in Fig. 1. 17 is the cover for 6 and 18 is the cover for 1. The sleeve used to couple the device to the intake pipe is denoted by 20. 14 are the pipes coming to the coupling from the device. 21 are the couplings. 22 are the pipes leading from the couplings to the fire. The center pipe directly below the air intake at the intersection of the four way arms of the cruciform chamber device delivers air to the center of the fire while a proportionate amount of air is delivered to the other communicating compartments and hence by the outer pipes to the outer portions of the fire, in lesser proportion than by the center pipe. The need for more oxygen is greater in the center of the fire and less is needed at the outer portions. My cruciform arrangement of chambers and intersecting rows of depending pipes supplies such need accordingly.

I claim:

1. A smoke consuming device comprising an air heating box adapted to be located in the upper part of the fire box of a furnace and consisting of walls forming multiple communicating chambers radiating from a central chamber, an air intake pipe extending from said central chamber to the outside of the furnace, and pipes extending downward within the fire box from said chambers, said pipes being loosely mounted in the bottom walls of said chambers, and each pipe consisting of two members, and a cup like box flexibly connecting said members, substantially as described.

2. A smoke consuming device comprising an air heating box adapted to be located in the fire box of a furnace and consisting of two chambered members having notches in the middle for connection in cruciform shape, each member having a top lid and holes in the bottom walls, pipes extending downward loosely through said holes forming flexible connections, fastening means for said lids, and an air-intake pipe from said connection to the outside, substantially as described.

3. The combination with the fire box of a furnace, of an air heating box located near the top of said fire box, and pipes flexibly connected to the bottom of said air heating box and extending downward in the fire box, and means to supply outside air to said air-heating box, said pipes being in two sections having washers on their adjacent ends, and a double cup loosely enclosing said ends and fastened together forming a flexible coupling, substantially as described.

4. A smoke consuming device comprising a cruciform air heating box composed of two intersecting members, one member being a rectangular open box having partitions forming three chambers, the middle chamber hav-

ing openings in its side walls and partitions, the other member consisting of two rectangular open boxes joined together but spaced apart the width of the other member and having holes matching the side holes in the other member, a lid closing each member and fastening means therefor, an air intake to the middle chamber, and air outlet pipes depending from said chambers and flexibly connected thereto, substantially as described.

10 5. A smoke consuming device comprising an air heating box consisting of walls forming multiple communicating compartments arranged in cruciform shape adapted to be located in the upper part of the fire box of a furnace, an air intake pipe extending from the center compartment to the outside of the furnace and effecting equal distribution of air in four ways to the outer compartments, 20 and pipes extending downward from said compartments forming two cruciform intersecting rows of vertical pipes adapted to deliver air to the center and outer portions of the fire in the fire box, substantially as described.

25 6. A smoke consuming device comprising an air heating box consisting of walls forming multiple communicating chambers adapted to be located in the upper part of the fire box of a furnace, an air intake pipe extending from one chamber to the outside of the furnace, and multiple pipes extending downward within the fire box from said chambers for the downward passage of air, 30 said pipes being in two parts with the lower part flexibly connected to the upper part by means outside of said pipes to afford oscillation and full area of air passage, substantially as described.
